DESIGN FOR A TYPE COMPOSING MACHINE

Frank H. Poeppelmeier, Dayton, Ohio, assignor to Econotype, Inc., Dayton, Ohio, a corporation of Delaware

Application January 27, 1936, Serial No. 60,829

Term of patent 14 years

To all whom it may concern:

Be it known that I, Frank H. Poeppelmeier, a citizen of the United States, residing in the city of Dayton, in the county of Montgomery and State of Ohio, have invented a new, original, and ornamental Design for a Type Composing Machine, of which the following is a specification, reference being had to the accompanying drawing, forming part thereof.

The figure is a perspective view of a type composing machine, showing my new design.

I claim:

The ornamental design for a type composing machine, as shown.

FRANK H. POEPPELMEIER.
